UNITED STATES PATENT OFFICE.

ISRAEL H. KINCH, OF PLEASANTVILLE, NEW YORK.

DESIGN FOR A HAT AND CLOTHES RACK.

Specification forming part of Design No. 5,822, dated April 30, 1872.

To all whom it may concern:

Be it known that I, ISRAEL H. KINCH, of Pleasantville, in the county of Westchester and in the State of New York, have invented certain new and useful Improvements in Design for a Hat and Clothes Rack; and do hereby declare that the following is a full, clear, and exact description thereof, reference being had to the accompanying drawing and to the letters of reference marked thereon making a part of this specification.

The nature of my design consists in a hat and clothes rack, formed as hereinafter more fully set forth.

A and B represent the sections of my rack arranged alternately, as shown. These sections are formed of bars *a* bent or cut in the manner shown, and connected together in the center and at the ends, the pins extending in front and forming the hooks or pins *b*. The

bars *a* each form one side of a section, A, and one side of a section, B, the sides of the sections A being bent inward and those of the sections B bent outward. Thus the sections A form somewhat of a star or diamond, while the sections B form octagonal figures.

This rack may be made of any length desired, only so as to preserve the alternating of the sections A and B.

What I claim is—

One or more sections, A, with one or more sections, B, as shown and described.

In testimony that I claim the foregoing I have hereunto set my hand this 15th day of February, 1872.

ISRAEL H. KINCH.
